DIGESTER APPARATUS

William H. Shipman, Akron, Ohio, assignor to
 The Babcock & Wilcox Company, Newark,
 N. J., a corporation of New Jersey

Application May 2, 1935, Serial No. 19,369

14 Claims.

(Cl. 92—7)

This invention relates to material handling apparatus and it is more particularly concerned with chemical apparatus for handling fluids. It is exemplified herein in connection with a digester for the preparation of wood pulp.

To effectively maintain digester reactions incident to the breaking down of wood chips to form pulp, a hot liquor of a pre-determined chemical constituency is circulated through the digester, in modern high capacity units. To complete the chemical reactions in the digester in a minimum of time, it is important that effective control of pressure and temperature be maintained, along with the control of the volume of liquor circulated. The apparatus for maintaining such control includes a fluid pressure relief line and a pressure control connection with the upper part of the digester. This invention is particularly directed to improvements in this type of apparatus.

Even when the relief line connections are at the very top of the digester the relief fluid often carries such a high percentage of solids that pumps and other apparatus handling the fluid might quickly be rendered inoperative. To prevent this a screen is provided for the relief line, and it is a desideratum that the screen be located within the digester or the digester nozzle. In the present instance, the screen is readily detachable and of such construction that it can be easily cleaned. Furthermore, when the screen is removed for cleaning a relief line outlet chamber is entirely exposed so that it may be readily cleaned. The invention contemplates also a screen structure, the removal of which does not involve the detachment or attachment of the relief line connection with the digester.

The invention also contemplates a digester construction which guides and maintains a rotary chip distributor and permits that distributor to be quickly and accurately positioned within the screen and within the charging port of the digester.

A further and more specific object of the invention is to provide a digester relief line screen which forms a continuation of the digester charging port and is formed with chip distributor guides aligning with similar guides formed in the neck of the digester.

The invention contemplates a rotary chip distributor which imparts a lateral force to the chips and causes such an arrangement of the chips in the digester that the cooking operations are enhanced and a better quality of pulp thus assured. It contemplates a chip distributor having a rotary impeller located below the relief line screen, and

in such a position that the screen or strainer will not be subject to damage by the constant hammering of the chips against it. The invention further contemplates a relief line screen structure which will not provide a ledge extending into the digester. Lodging of the chips on such ledges is thereby prevented, and excessive wear upon the screen structure caused by the flow and rubbing of the chips is at a minimum.

The invention will be described with reference to the accompanying drawings, in which:

Fig. 1 is a vertical section through the top of the digester showing the rotary chip distributor as it is used when the digester is being charged.

Fig. 2 is a partial perspective view showing the top of the digester, the trolley frame for carrying the chip distributor, and the automatic relief valve and piping connecting it to the nozzle of the digester.

Fig. 3 is a vertical section showing the screen structure and the chip distributor spider guide on a larger scale.

Fig. 4 is a view looking downwardly from the plane indicated on the line 4—4 of Fig. 3.

The digester structure shown in Fig. 1 of the drawings includes a metallic shell 10 supporting a flanged collar 12 at the neck of the digester. Within the collar 12 is a sleeve construction 14 recessed to provide the space 16 which becomes a part of the relief fluid screen chamber. This sleeve has a flange 18 which rests upon the top of the collar 12 and maintains the sleeve in operative position.

The lower end of the sleeve 14 extends within the digester to a point substantially beyond the shell 10 where its inner end 20 is belled. This promotes anchoring of the lining 22 around the charging port of the digester.

The drawings also show the sleeve 14 as forming guideways for the arms 24 of a distributor spider. As illustrated, and more particularly shown in Fig. 3 of the drawings, these guideways are provided by ribs 26 and 28 integral with the metal of the sleeve.

At the lower end of each guideway there is a seat for a distributor spider arm. Each seat is indicated in Fig. 3 as having an inclined face 30 corresponding to a similar inclined surface on each spider arm. Each guideway is closed off at its lower end by the material of the sleeve which forms a shoulder 32. The chip distributing apparatus is thereby correctly centered and adequately maintained in operative position within the charging port of the digester.

The sleeve 14 is preferably formed so as to

correspond with the configuration of the collar 12, and it communicates at one side of the digester with a relief pipe 34 which is shown extending through the collar 12. This relief pipe in turn communicates with the space 16 which is closed off by the sleeve and the screen 36 to form a relief line chamber extending around the perimeter of the charging port. The screen 36 preferably rests upon the shoulder 38 at the 10 lower end of the recessed portion of the collar 12, and its inside diameter is preferably identical with that of the inside diameter of the lower portion of the sleeve. The screen is preferably formed of metal with upper and lower outwardly 15 extending flanges 40 and 42 respectively. The lower of these flanges is shown seated on the shoulder 38 while the upper flange 40 closes off the top of the space which forms the relief line screen chamber.

20 The screen or strainer 36 is provided on its inner surface with ribs forming upright guideways which are continuations of the guideways between the ribs 26 and 28 of the sleeve 14. As shown, the upper parts 44 and 46 of these ribs 25 are upwardly divergent so as to facilitate the entering and placement of the chip distributor in operative position. Their lower ends 48 and 50 are shown parallel to each other and parallel to the axis of the charging port of the digester.

30 The chip distributor which is, during the charging of the digester, temporarily positioned within the charging port, includes a rotating distributor element or, impeller, 52 secured to the lower end of an upright shaft 54 journaled 35 in a bearing 56 preferably integral with the spider arms 24. The upper end of the shaft 54 is connected by means of a universal joint 57 and the telescoping shaft construction 58 to a second universal joint 60. This last universal joint is also connected to the end of an upright 40 intermediate shaft 62 rotatably mounted in a journal 64 supported by a carriage 66. The shaft 62 is connected by means of bevel gears 68 and 70 with a driving shaft 72 which is shown coaxial with the shaft 14 of the motor 76.

45 The motor 76 may be also connected to a belt and pulley device 78 so that it may rotate the hopper 80 through the transmission 82 and a belt 84 extending around the grooved wheel 86 rigid with the hopper. The hopper may rotate 50 on rollers 90 which are mounted upon horizontal axes and may be guided by rollers 92 which are rotatable upon vertical axes.

55 In the operation of the chip distributor the chips are delivered to the hopper 94 in a steady stream and are evenly spread by the rotating hopper 80 before they fall through chute 98 and thence through the charging port of the digester. As they pass downwardly from the charging port 60 they are engaged by the impeller 52 and evenly distributed over the digester so as to avoid undesirable stratifications.

65 The motor as well as the rotating hopper 80 and all of the superposed mechanism may be carried by a frame 100 which is a part of the carriage movable along a trackway from one digester to another. After the digester is fully charged, the carriage 100 is moved along the track, the telescoping shaft mechanism automatically disconnecting the shaft 54. Thereafter the distributor element may be freely elevated from its illustrated position, the chute 98 removed, and the cover 104 for the digester placed in position so that the cooking operation can begin.

70 Fig. 2 shows the relief pipe 34 connected to

the automatic relief valve 106 at one end and to a digester coupling at the other end. This coupling includes a flanged and threaded nipple 108 telescoped within an exterior nipple 110. A coupling ring 112 presses the gasket 114 against the latter nipple to tightly maintain the assembled parts in their operative positions.

75 Whereas the invention has been described with reference to the particular apparatus shown in the drawings it is not limited to all the limits thereof, but is of a scope commensurate with the subjoined claims.

What is claimed is:

1. Apparatus of the class described comprising, in combination, a digester, a material distributor temporarily insertible through a charging opening in the top of the digester, a structure framing the opening and formed to provide seats for the distributor, means on said structure forming guides leading to said seats, 20 and an annular strainer having guideways formed thereon as continuations of the above mentioned guides.

2. In combination, a digester having a recessed nozzle, a chip distributor, a relief line strainer 25 ring seated within the nozzle recess, and means on said ring for guiding the distributor into its operative position.

3. In combination, a digester having a recessed charging nozzle, a channel-shaped screen seated 30 within the recess and cooperating with the walls thereof to form a relief fluid chamber, a relief line extending through the side of the nozzle and communicating with the chamber, a chip distributor adapted to be temporarily seated and 35 operated within the nozzle, a spider extending across the nozzle and supporting the distributor, aligned guideways formed by parts on the nozzle and the screen for guiding the ends of the spider into operative position, and stops formed in the 40 nozzle at the lower ends of the guideways.

4. In a digester, an exterior metal casing formed with a charging opening at the top, a nozzle defining the opening, a flanged sleeve construction extending through the frame and the 45 opening to a position within the casing with the flange of the sleeve resting upon the top of the nozzle so that the sleeve is thereby supported in its operative position, a digester fluid relief line extending through the side of the nozzle 50 and communicating with a recess formed in the upper part of the sleeve, a digester lining closely fitting around the inner ends of the sleeve and secured to the casing, and an easily detachable metallic strainer ring disposed within the recess 55 and combining with the walls thereof to form a relief fluid chamber communicating with the relief line.

5. In combination, a digester having a charging nozzle at the top thereof, a recessed and flanged 60 metallic sleeve extending into the opening, and an annular metallic strainer which is channel shaped in cross section so that it will cooperate with the sides of the recess walls to form a fluid chamber 65 for the digester relief line.

6. In combination, a digester having a metallic shell, an acid proof lining within the shell, a flanged collar extending through a nozzle at the top of the digester and having a lining contacting 70 flange at its inner end, the collar being supported from the top of the digester, a metallic strainer ring cooperating with an annular recess in the collar for forming an annular fluid relief chamber, a distributor spider, and guideways formed 75

on the collar and the strainer for guiding the spider into its operative position.

7. Apparatus of the class described comprising, in combination, a digester, a material distributor insertible temporarily through the digester nozzle, a structure framing the opening and formed to provide seats for the distributor, said structure forming guideways leading to said seats and an annular strainer having guideways formed thereon as continuations of the above mentioned guides, means for discharging a stream of chips through the nozzle so that they contact with the distributor, and means for rotating the distributor.
- 10 8. In combination, a digester formed with a recessed nozzle, a chip distributor, a relief line strainer ring seated within the nozzle recess, and aligned means on said ring and the nozzle for guiding the distributor into its operative position.
- 15 9. In combination, a digester having a metallic shell, an acid proof lining within the shell, a flanged collar extending through a nozzle at the top of the digester and having a lining contacting flange at its inner end, the collar being supported from the top of the digester, a metallic strainer ring cooperating with an annular recess in the collar for forming an annular fluid relief chamber, a distributor spider, and aligning ribs formed on the collar and the strainer for guiding
- 20 the spider into its operative position.
- 25 10. In combination, a digester formed with a charging opening the walls of which present an annular recess, a distributor, distributor supports, a readily detachable sheet metal strainer ring seated within the recess and forming with the walls thereof an annular relief line chamber, and means on said ring for guiding the distributor toward its operative position on said supports.
- 30 11. In combination, a digester formed with an opening which is bounded by a recessed frame, a channel shaped strainer seated within the recess and cooperating with the walls thereof to form a fluid chamber, a relief line extending through the frame and communicating with the chamber, a

material distributor adapted to be temporarily seated and operated within the opening, a distributor support extending across the opening, aligned guideways formed by parts of the frame and the screen for guiding the ends of the support into operative position, and seats formed in the frame at the ends of the guideways.

12. In combination, a digester having a recessed charging nozzle, a screen seated within the recess and cooperating with the walls thereof to form a relief fluid chamber, a relief line extending through the side of the nozzle and communicating with the chamber, a rotatable chip distributor adapted to be temporarily seated and operated within the nozzle, a distributor support extending across the opening, aligned guideways formed by parts on the nozzle and the screen for guiding the ends of the spider into operative position, and stops formed in the frame at the lower ends of the guideways.

13. In a digester, an exterior metal casing formed with a charging opening at the top, a nozzle defining the opening, a flanged sleeve construction extending through the frame and the opening to a position within the casing with the flange of the sleeve resting upon the top of the nozzle so that the sleeve is thereby supported in its operative position, a digester fluid relief line extending through the side of the nozzle and communicating with a recess formed in the upper part of the sleeve, a digester lining closely fitting around the inner ends of the sleeve and secured to the casing, and an easily detachable strainer ring closing the recess and combining with the walls thereof to form a relief fluid chamber communicating with the relief line.

14. In combination, a digester having a charging nozzle at the top thereof, a recessed metallic sleeve extending into the opening, and an annular strainer which is channel shaped in cross section so that it will cooperate with the sides of the recess walls to form a fluid chamber for the digester relief line.

WILLIAM H. SHIPMAN.
